Application December 3, 1934, Serial No. 755,750

41 Claims. (Cl. 12—14)

The present invention relates to methods of and machines for use in manufacturing boots and shoes and is herein illustrated in its application to the manufacture of pre-welted shoes, 5 that is, shoes in which a welt is attached to the margin of the upper before the upper is lasted. In certain of its aspects the invention relates particularly to the lasting of that type of pre-welted shoe having the welt extended about its heel portion.

Objects of the present invention are to reduce the cost of manufacturing pre-welted shoes and to provide a machine which will easily and accurately shape a pre-welted upper to its last.

15 In its application to methods of lasting shoes the invention consists in wiping an upper on a last heightwise thereof toward the last bottom while holding the shoe against heightwise movement by lasting wipers positioned, at least in part, 20 at the sides of the shoe. Preferably the upper is pulled over the toe end of the last prior to the lasting operation.

Features of the invention in its application to lasting machines reside in shank lasting members, 25 means for shaping the forepart of an upper on its last, herein illustrated as forepart wipers constructed and arranged to engage the forepart of a pre-welted upper within the welt crease, and means for urging the shank lasting members 30 toward each other whereby said members, bearing against the shoe bottom, oppose movement of the last heightwise thereof during the forepart lasting operation, thereby obviating the requirement of a holdown member such as is usually 35 provided in bed lasting machines. The illustrated shank lasting members comprise elongated heel wipers constructed and arranged to engage the heel and shank portions of a pre-welted upper within the welt crease.

40 In its application to machines for use in effecting adhesive attachment of an outsole to a lasted shoe the invention comprises a sole-laying member, a slide to which the member is pivoted, a carrier for the slide, herein illustrated as a 45 bracket constructed and arranged to swing about a vertical axis, means for adjusting the slide lengthwise thereof relatively to the carrier bracket, and adjusting means for so locating the sole-laying member that its longitudinal median line 50 is arranged at any one of a series of predetermined angles to the slide, said angle being determined, in the illustrated machine, in accordance with the size of the shoe to be operated upon. Thus it will be understood that the sole-laying member, after it has been swung into sole-laying

position, requires no further angular adjustment to cause its longitudinal median line to be arranged coincidentally with the longitudinal median line of the supported shoe. In order to relieve the operator of the duty of adjusting the 5 sole-laying member lengthwise thereof relatively to the supported shoe there is provided, in accordance with a further feature of the invention, an adjustable stop for arresting the sole-laying member in any one of a series of predetermined 10 positions lengthwise of the supported shoe.

In lasting pre-welted shoes the width of the margin to be wiped over the last bottom is determined by the extent to which the wipers are advanced. Heretofore the operator has been required to determine the proper extent of advancing movement of the wipers. It is an object of the present invention to relieve the operator of this duty and accordingly a further feature of the invention, in its application to lasting machines, 15 consists of a heel pad or band and a heel wiper characterized by interengaging surfaces on the wiper and the pad, respectively, arranged to arrest the wiper by their interengagement, and characterized further by the disposition of a 20 portion of the thickness of the wiper below the level of the top of the pad, said wiper, as herein illustrated, being provided with a thin overwiping margin extending to a measured extent beyond 25 its heel-pad-engaging surface. In order to pre-determine the extent of overwiping of the toe wipers, each of said wipers is provided, in accordance 30 with a further feature of the invention, with an overwiping margin of predetermined width and of such a thickness that said margin may advance between the welt and the upper of a pre-welted shoe substantially to the seam whereby the 35 welt is secured to the upper without stretching the seam, said wipers being characterized by a 40 face extending downwardly from the overwiping margin, preferably at an obtuse angle thereto, said faces, as herein illustrated, serving to arrest the toe wipers at the limit of their overwiping movement by engagement with the portion of the 45 upper adjacent to the edge of the last bottom.

These and other aspects and features of the invention will now be described with reference to the accompanying drawings and will be pointed out in the appended claims.

50 In the drawings,
Fig. 1 is a front elevation of a bed lasting machine embodying the features of the present invention, certain parts not required for the description of the present invention being omitted; 55 Fig. 2 is a plan view illustrating particularly

the lasting wiper plates and the outsole-attaching mechanism;

Fig. 3 is a side elevation of a portion of the sole-attaching mechanism looking in the direction of the arrow III in Fig. 2;

Fig. 4 is a sectional view taken substantially on the line IV—IV of Fig. 2;

Fig. 5 is a detail view in front elevation illustrating a sole-laying presser plate and associated parts;

Fig. 6 is a side elevation of the sole laying mechanism broken away from the body of the machine;

Fig. 7 is a sectional view taken substantially on the line VII—VII of Fig. 2;

Fig. 8 is a sectional view of one of the toe wiper plates taken substantially on the line VIII—VIII of Fig. 2;

Fig. 9 is a plan view of the heel lasting mechanism in advanced position, the heel end of a pre-welted shoe being shown in jacked position;

Fig. 10 is a front elevation partly in section on the line X—X of Fig. 12 illustrating the heel lasting mechanism and a jacked shoe in the same position in which they are shown in Fig. 9;

Fig. 11 is a detail sectional view similar to Fig. 10 showing one of the heel wipers in retracted position;

Fig. 12 is a plan view of the heel band and its supporting and adjusting mechanisms;

Fig. 13 is a plan view looking upwardly at the heel band and parts of its supporting and adjusting mechanisms, and

Fig. 14 is a sectional view taken substantially on the line XIV—XIV of Fig. 12.

Referring to Fig. 1, the illustrated machine comprises a toe head 20 and a heel head 22 mounted on a standard 24, the toe head 20 being adjustable lengthwise of a supported pre-welted shoe 26 toward and from the heel head 22. Mounted in the toe head for predetermined movement lengthwise and widthwise of the shoe 26 is a pair of toe wiper plates 28 for wiping the welted margin of the upper over the margin of the last bottom, said wipers being constructed and arranged to extend rearwardly of the supported shoe to the region of its ball line. Mounted in the heel head for predetermined movement forwardly of and widthwise of the shoe 26 is a pair of heel wiper plates 30 constructed and arranged to extend forwardly of the supported shoe to the region of its ball line. The illustrated wiper plates in their overwiped positions, as shown in Fig. 2, substantially enclose the shoe and support the welt throughout substantially its entire extent while a cement-treated outsole is attached thereto. In order to reduce to a minimum the interchange of wipers, the wipers are constructed and arranged to operate upon shoes within a given run of sizes. For example, the illustrated wipers are constructed and arranged to operate upon three sizes of infants' shoes, namely, 5, 5½ and 6. The length of the wipers is measured from the smallest size of shoe in the run in order to avoid the necessity of overlapping the adjacent ends of the wipers when operating upon shoes of the smallest size. The contour, or pattern, of the wiper plates is preferably taken from the intermediate size, that is, size 5½ in the case of the illustrated wipers, while the line of the heel wipers, as seen in side elevation (Fig. 1), hereinafter referred to as their profile, is preferably determined by the profile of shoes of the largest size within the run in order that the wipers may press the shank portion of the upper firmly

against the last bottom in all sizes of shoes within the run.

At its toe end the shoe 26 is supported upon a toe post 32 while at its heel end the shoe is supported upon a jack post 34, the upper end of which is provided with a pin constructed and arranged for engagement within the pin hole provided in the last. In order to move the shoe 26 rearwardly thereof into engagement with a heel pad or band 36 (Fig. 10) the jack post 34 is constructed and arranged for movement lengthwise of the shoe 26, said movement being effected by a hand wheel 38 (Fig. 1) having rack and pinion connections with the jack post.

In order to upwipe the toe end of the supported shoe 26 the toe wipers 28 are moved upwardly by actuating a double-ended treadle 40 pivoted to the base of the standard 24 and provided with suitable connections for imparting heightwise movement to a vertically movable block 42 extending downwardly from the toe head 20.

Referring now to Fig. 10, the illustrated heel wiper plates 30 have their overwiping margins 44 reduced in thickness sufficiently to permit them to enter the welt crease of a pre-welted upper 25 without unduly straining the seam 45 whereby a welt 41 is secured to the upper. For example, an overwiping margin $\frac{1}{2}$ and of an inch thick and $\frac{3}{8}$ and wide has been found to be well adapted for use in lasting pre-welted shoes in infants' sizes two to eight, inclusive. The upper surface of the overwiping margin 44 is disposed in the plane of the upper surface of the body portion of the wiper plate. Extending outwardly of the wiper from the under surface of the overwiping margin 44 is a beveled face 46 of substantially the same width as the upper edge face 48 of the heel band 36. The illustrated heel band has its upper edge face beveled to the same degree as the face 46 of the wiper plate, the inner extremity of the upper edge face 48 of the band being positioned in contact with the under surface of the overwiping margin 44 as the wiper 30 advances into the welt crease (Fig. 10). The contact between the heel band and the overwiping margin 44 being maintained during the overwiping operation, it will be seen that the heel band is permitted to engage the portion of the upper adjacent to the heel wipers, as illustrated in Fig. 10, and consequently the heel band will not leave the upper. The upper edge face 48 of the heel band also serves as a means for arresting the heel wipers 30 at the limit of their overwiping movement, thereby predetermining the extent of said overwiping movement and insuring the proper location of the welted margin of the upper upon the last bottom.

In order that the heel band 36 may be accurately positioned relatively to the heel wiper plates 30, means is provided for adjusting the band lengthwise and widthwise of the supported shoe 26 and for moving the ends of the heel band toward and from each other. Referring now to Figs. 10, 12, 13 and 14, the members which support the heel band are secured to a carrier 50 which is slidably mounted upon a plate 52 (Fig. 14) secured by screws 54 to the bed plate 56 which supports the heel wiper mechanism. As illustrated in Fig. 14, the plate 52 is U-shaped in cross section, the upright portions 58 of said plate forming the side walls of the guideway in which the heel band carrier 50 is positioned. The heel band carrier is somewhat narrower than its guideway, the space between the side walls 75

60 of the guideway and the respective edge faces 62 of the heel band carrier being taken up by screws 64 in the uprights 58, the ends of which are flattened for guiding engagement with the edge faces 62 of the heel band carrier. By adjusting the screws 64, the position of the heel band carrier 50, and consequently of the heel band 36, widthwise of the supported shoe may be varied within the limits afforded by the uprights 58.

10 Lock nuts 65 are provided for securing the screws 64 in their respective positions. In order to adjust the heel band lengthwise of the supported shoe a thumb screw 66 (Fig. 12) is threaded into a tapped hole in the heel head and arranged to engage the downwardly extending rear end portion 68 (Fig. 10) of the heel band carrier 50 in order to move the carrier and the heel band assembly mounted thereon forwardly of the supported shoe. The heel band carrier is urged against the end of the thumb screw 66 by a compression spring 70 positioned between the downwardly extending end portion 68 of the carrier and an angle bracket 72 secured to the under surface of the plate 52, said spring being retained in position by pins 14 mounted in the bracket 72 and the end portion 68, respectively, and arranged to receive the ends of the compression spring. As illustrated in Fig. 13, the plate 52 is cut away at 76 in order to provide space for a movement of the end portion 68 of the heel band carrier lengthwise of the supported shoe sufficient to permit the required lengthwise adjustment of the heel band. A lock nut 78 (Fig. 12) on the thumb screw 66 may be employed to secure the screw in adjusted position.

The illustrated means for adjusting the ends of the heel band 36 toward and from each other consists of adjusting screws 80 (Fig. 12) having threaded engagement in tapped holes located at 40 opposite ends of a curved plate 82 secured by screws 84 (Fig. 10) to the upwardly extending forward end portion 86 of the heel band carrier 50. The adjusting screws 80 are arranged for engagement with a pair of arms 88 (Fig. 12) pivoted to the curved plate 82 and arranged to engage the outer face of the heel band 36. Each of the arms 88 is bifurcated to permit it to straddle the plate 82, said plate 82 serving to prevent heightwise movement of the arms 88.

50 The heel band is removably supported upon the curved plate 82 and the arms 88 by three clips 90 (Fig. 13) one of which is secured to said plate 82 and the other two to the arms 88, respectively. Each of said clips has a pin and slot connection 55 with its supporting member (Fig. 10) in order to permit adjustment of the clips heightwise of the supported shoe, clamping nuts 91 being provided for securing the respective clips in adjusted position. The heel band is held against the convex surfaces of the plate 82 and the swinging arms 88 pivoted thereto by two brackets 92 (Fig. 13) provided, respectively, with pin and slot connections to the forward ends of the swinging arms 88 and arranged to engage the end faces 65 of the heel pad. Nuts 93 are provided for clamping the brackets 92 to the swinging arms 88. After the screws 80 have been adjusted in order to provide the desired spacing of the ends of the heel band from each other they may be secured in adjusted position by internally threaded sleeves 94 threaded to the screws 80 and provided, respectively, with capstan heads 96 whereby the sleeves may conveniently be clamped against the curved plate 82.

70 Referring now to the forepart lasting mecha-

nism, each of the illustrated toe wiper plates 28 is provided with a thin overwiping margin 98 (Fig. 8) of uniform and predetermined width and adjacent to the under surface of the margin 98 a beveled face 100 is formed in the wiper plate for engagement with the upper along a line substantially adjacent to the edge of the last bottom. The engagement of the beveled face 100 with the upper arrests the wiper plate and thus determines the extent of its overwiping movement. 10 The inclination of the beveled face 100 is such that it engages a very limited extent of the upper, heightwise thereof, in the region of the last bottom. The beveled face 100 is extended downwardly and outwardly beyond its line of engagement with the upper and preferably to the under surface of the body portion of the wiper plate in order to prevent the formation of an objectionably conspicuous imprint of said beveled face on the upper. While the invention does 20 not prescribe the angle of the beveled face 100 to the overwiping margin 98, it has been found that an edge face arranged at an angle of 130° to the overwiping margin is well adapted to arrest the wiper at the limit of its overwiping movement.

In lasting pre-welted shoes it has been found that in order to shape the shank portion of the upper accurately to the last the wiper at the inside portion of the shank is required to exert 30 a greater force upon the upper than is required of the wiper at the outside of the shank. Consequently the last must be held against movement widthwise thereof during the shank lasting operation in order to prevent the unbalanced 35 wiping forces at opposite sides of the shank portion of the shoe from dislocating the last and thereby making it impossible for the elongated heel wipers 38 to perform a perfect shank lasting operation. The heel band 36, acting alone, 40 has been found incapable of holding the last against widthwise movement during the shank lasting operation and accordingly the toe wiper plates 28 are preferably advanced prior to the shank lasting operation in order to bring their 45 beveled faces 100 into engagement with the upper on the last, in which position the toe wiper plates cooperate with the heel band to hold the last against widthwise movement while the operator 50 actuates the lever 174 (Fig. 9) to advance the elongated heel wipers 38 to the limit of their overwiping movement.

The illustrated wiper plates serve not only to overwipe the welted margin of the supported shoe 55 but also to support the welt while an outsole 50 which has been treated with adhesive is pressed against the shoe bottom in order to hold the upper in lasted position until the outsole is permanently stitched to the welt. In the illustrated machine a series of interchangeable sole-laying 60 presser plates is provided, one of which is illustrated at 102 in Fig. 2. The sole-laying presser plate 102 is latched to a holder herein illustrated as an arched plate 103 (Fig. 5) which is pivoted to one end of a horizontal presser arm 104 by 65 means of a headed screw 105 extending upwardly through a counter-bored hole in the holder plate 103, said hole being made somewhat larger than the screw in order to provide a loose fit of the screw 105 in the holder plate thereby permitting the plate to arrange itself to press uniformly upon the outsole of the supported shoe. In order that the presser plate 102 may conveniently be removed from the machine and another plate of different size substituted therefor the presser 70 75

plate is removably attached to the holder plate 103 by latching devices illustrated in Fig. 5 comprising studs 162 extending upwardly from opposite ends of the presser plate and arranged to be positioned in holes provided at opposite ends of the holder plate 103. The studs 162 are notched (Fig. 7) for the reception of latch pins 164, each of which is slidably mounted in a hole extending widthwise of the holder plate and radially from the stud-receiving hole to the rear edge face of the plate. Each of the latch pins 164 is pressed against its stud 162 by a spring 166 (Fig. 2) secured by a screw 168 to the center portion of the holder plate 103, the free ends of the respective springs 166 being slotted for engagement with the peripherally grooved heads 170 of the latch pins 164. When it is desired to remove the presser plate 102 in order to substitute therefor another presser plate of different size all that is required of the operator is to press the free ends of the springs 166 rearwardly from the holder plate 103 in order to disengage the latch pins 164 from the studs 162 thereby permitting the presser plate to drop from the holder plate 103. The illustrated sole-laying plate 102 has the same general outline as the outsole to be attached to the bottom of the illustrated shoe 26 and is arranged to conform to the profile of the last bottom. The presser arm 104 is slidably mounted in a carrier herein illustrated as a swinging bracket 106 (Fig. 6), the hub of which is sleeved on a vertically movable post 108. For the purpose of moving the presser plate 102 downwardly as it is brought into sole-pressing position the hub of the bracket 106 is provided with a spiral slot 110 which takes a stud 112 extending outwardly from the post 108 and arranged to lower and raise the bracket 106 automatically as it is swung toward and from operative position. The bracket 106 is yieldingly held at the limit of its counterclockwise movement, as seen in Fig. 2, by a spring 114, one end of which is secured to the machine frame. A treadle spring 115 holds the post 108 at the limit of its upward movement. The post 108 is moved downwardly in order to press the plate 102 against an outsole on the bottom of the supported shoe by a treadle 116 connected to the post 108 by a link 118. The treadle is associated with a locking bar 120 and a pawl 121, and a knee lever 122 is operatively connected to the pawl by a link 123 whereby a rearward movement of said lever 122 operates to disengage the pawl from the locking bar 120, thereby releasing the treadle 116 and permitting the post 108 to be returned by the treadle spring 115 to its elevated position. As the sole-laying presser plate 102 is lifted off the outsole after the outsole has been pressed against the shoe bottom the spring 114 swings the bracket 106 counterclockwise, as seen in Fig. 2, thereby moving the sole-laying plate into a position in which it offers no obstruction to the removal of the shoe from the machine and to the introduction of another shoe to be operated upon.

In order that the sole-laying presser plate 102 may be located accurately in sole-pressing position by swinging the presser arm 104 to a predetermined limit there is provided in the illustrated machine means for arresting the clockwise movement of the presser assembly, as seen in Fig. 2, in any one of a series of positions depending upon the size of the shoe which is being operated upon. As herein illustrated, the means for arresting the presser assembly consists of a bracket 124, a horizontal arm of which is secured to the

machine frame and a vertical arm of which extends upwardly from the horizontal arm into the path of a thumb screw 126 (Fig. 3) carried by a bracket 128 which is secured to the under surface of the swinging bracket 106. The thumb screw 126 is threaded to a stud 130 projecting from the bracket 128, said thumb screw being yieldingly held in any one of its adjustive positions by a retarder or spring-pressed plug 132 slidably mounted in a sleeve 134 extending upwardly from the stud 130, said plug being constructed and arranged for frictional engagement with the threads of the thumb screw 126. In order to indicate the adjustive positions of the thumb screw 126, there is provided a bracket 136 having inscribed on the upper face of its horizontal arm a scale measuring in terms of shoe sizes the adjustive positions of the thumb screw. An indicator in the form of a flanged collar 138 on the thumb screw is arranged to register with the scale. It will be seen, upon examination of Fig. 2, that for every adjustment of the thumb screw 126 a corresponding adjustment of the presser plate 102 widthwise thereof is necessary in order to position the plate in sole-pressing position since the plate moves into its operative position in an arcuate path about the post 108 and consequently moves both widthwise and lengthwise of the supported shoe as it approaches its operative position. In the illustrated machine the widthwise adjustment of the sole-laying presser plate 102 is predetermined by adjusting a thumb screw 140 threaded to a tapped bore extending lengthwise of the presser arm 104, said thumb screw being held from lengthwise movement relatively to the swinging bracket 106 by a bracket 142 secured to the swinging bracket and having its bifurcated end arranged at right angles to the thumb screw and fitted between peripheral flanges 143 provided thereon. The lengthwise adjustment of the presser arm 104 in the swinging bracket 106 is measured in terms of shoe sizes by an indicator or finger 144 secured to the arm 104 and arranged to register with a scale inscribed on a plate 146 secured to the upper surface of the swinging bracket. In order that the longitudinal median line of the presser plate 102 may substantially coincide with the longitudinal median line of the supported shoe when the plate is in operative position, it will be seen that a further adjustment is required in view of the fact that the longitudinal median line of the presser plate is continually changing its direction as the operator swings the presser assembly about the post 108 to bring the presser plate 102 into operative position. Accordingly, for every adjustment of the thumb screw 126 the illustrated organization affords a corresponding adjustment of the angle of the longitudinal median line of the presser plate to the presser arm 104 in order that the presser plate may be positioned in alinement with the supported shoe as the presser assembly comes to the limit of its clockwise movement, as seen in Fig. 2. In the illustrated machine, angular adjustment of the presser plate 102 relatively to the presser arm 104 is effected by a thumb screw 148. The thumb screw is threaded to a cylindrical pin 150 which is supported by a flange 152 (Fig. 4) within a guideway provided in the under surface of the presser arm 104. The thumb screw 148 is grooved at each end to receive bifurcated upstanding portions 154 of an arm 156 secured to the holder plate 103 which supports the sole-laying presser plate 102. The illustrated construction permits 75

the presser plate to swing freely on the pivot screw 105 in order to adjust itself to the profile of the bottom of the shoe which is being operated upon. In order to measure the angular adjustment of the presser plate 102 relatively to the presser arm 104 in terms of shoe sizes an arcuate plate 158 having a suitable scale inscribed thereon is secured to the under surface of the presser arm 104 with its axis of curvature coincidental with the axis of adjustive movement of the presser plate 102 and an indicator or finger plate 163 is secured to the arm 156 and arranged to register with said scale.

In the use of the illustrated machine in the manufacture of pre-welted shoes, a pre-welted upper which has previously been assembled on its last and has had its toe end pulled over the last is positioned upon the work supports of the machine. Preferably the sole-attaching face of the welt has previously been treated with adhesive such, for example, as rubber cement or latex, and an outsole to be attached to the shoe bottom has also been so treated. Before the pulled-over shoe is positioned in the lasting machine, the tacks, if any, which have been driven through the welted margin of the upper in order to secure the upper in pulled-over position on the last are removed. After the shoe has been mounted on the work supports of the lasting machine the heel wipers 30 are permitted to be advanced somewhat by a tension spring 172 (Fig. 9) connecting the heel wiper operating lever 174 to the heel head 22 thereby moving the overwiping margins at the forward ends of the respective heel wipers into the welt crease and inwardly over the last bottom in the region of the ball line of the supported shoe, but not, however, to the limit of their overwiping movement. The operator now turns the jack post hand wheel 38 in a counter-clockwise direction, as seen in Fig. 1, in order to bring the supported shoe into the position illustrated in Figs. 9 and 10, in which position the supported shoe is pressed firmly against the heel band 36 and the heel wipers underlie the welt 47 throughout their entire extent. The operator now adjusts the toe head lengthwise of the supported shoe, if necessary, and then actuates the double-ended treadle 40 (Fig. 1) to lift the toe head 20, at the same time pressing the toe wiper plates 28 against the supported shoe in order to wipe the upper heightwise of the last toward the last bottom. During the upwiping operation the last is held from upward movement by the forward ends of the heel wiper plates 30 which, as has been stated, are held in over the last by the tension spring 172 and therefore serve as a hold-down to prevent any upward movement of the toe end of the shoe during the upwiping operation. At the completion of the upwiping operation the toe wipers are advanced into the welt crease and the welted margin at the toe end of the upper is overwiped to a limit which is predetermined by the engagement of the beveled faces 100 of the respective toe wipers with the forepart of the upper adjacent to the welt crease. The operator now advances the elongated heel wipers 30 to the limit of their overwiping movement. The wipers remain in their respective overwiped positions in order to support the welt 47 during the sole-attaching operation. The treated outsole may now be placed on the sole-attaching face of the welt whereupon the sole-laying presser plate 102 is brought into sole-laying position, the adjustments necessary to predetermine said position having previously been made. The operator then

depresses the treadle 116, pressing the plate 102 against the outsole in order to secure the outsole to the welt. The presser plate 102 is then permitted to be returned to its retracted position by the spring 114 (Fig. 2) whereupon the toe wipers 5 and heel wipers are both retracted and the toe head 20 is returned to its lower position leaving the toe end of the shoe above the toe wiper plates, in which position the operator may conveniently lift it from the work supports and remove it from the machine.

While the invention in its application to the lasting of shoes is herein illustrated with reference to the lasting of shoes which have previously been pulled over it is to be understood that the invention is not thus limited in its scope but, on the contrary, is applicable to the lasting of shoes, particularly pre-welted shoes, which are not pulled over before being presented to the illustrated machine.

Having thus described our invention, what we claim as new and desire to secure by Letters Patent of the United States is:

1. That method of lasting shoes which comprises wiping an upper on a last heightwise thereof toward the last bottom while holding the shoe against heightwise movement by lasting wipers positioned, at least in part, at the sides of the shoe.

2. That method of lasting pre-welted shoes which comprises locating a pair of shank and heel wiper units in at least partly advanced position, positioning a pulled-over pre-welted upper relatively to said wipers whereby said wipers are arranged to engage the upper in the welt 30 crease with the inner margins of the wipers positioned over the last bottom, and thereafter wiping the toe end of the upper heightwise thereof toward the last bottom.

3. That method of lasting shoes which comprises positioning a last having an upper thereon in a lasting machine provided with toe-lasting wipers and lasting wipers positioned, at least in part, at the shank portion of the shoe, advancing the toe wipers until abutments provided 40 therein engage portions of the upper adjacent to the opposite sides faces of the forepart of the last thereby to hold the last from movement widthwise thereof, and thereafter advancing the shank wipers.

4. That method of lasting pre-welted shoes which comprises positioning a last having a pre-welted upper thereon in a lasting machine provided with toe-lasting wipers, lasting wipers positioned, at least in part, at the shank portion of the shoe, and a heel-embracing band, moving the last and upper rearwardly thereof into the band, advancing the toe wipers until abutment faces provided therein engage portions of the upper adjacent to the opposite side faces of the forepart 60 of the last thereby to hold the forepart of the last from movement widthwise thereof, and thereafter advancing the shank wipers while the heel-embracing band holds the rear part of the last from movement widthwise thereof.

5. A lasting machine having in combination shank lasting members, means for shaping the forepart of an upper on its last, and means for urging the shank lasting members toward each other whereby said members, bearing against the 70 shoe bottom, oppose movement of the last heightwise thereof during the forepart lasting operation.

6. A lasting machine having in combination shank lasting members, lasting members for wip- 75

- ing an upper on its last heightwise thereof toward the last bottom, and means for urging the shank lasting members toward each other whereby said members, bearing against the shoe bottom, oppose movement of the last heightwise thereof during the heightwise wiping operation.
7. A lasting machine having in combination elongated heel wipers constructed and arranged to overwipe the heel and shank portions of a shoe, means for shaping the forepart of an upper on its last, and yielding means for urging the wipers toward each other whereby said wipers, bearing against the shoe bottom, oppose movement of the last heightwise thereof during the forepart lasting operation.
8. A lasting machine having in combination elongated heel wipers constructed and arranged to engage the heel and shank portions of a pre-welted upper within the welt crease, means for shaping the forepart of the upper on its last, and means for urging the heel wipers toward each other whereby said members, bearing against the shoe bottom, oppose movement of the last heightwise thereof during the forepart lasting operation.
9. A lasting machine having in combination elongated heel wipers constructed and arranged to engage the heel and shank portions of a pre-welted upper within the welt crease, forepart wipers constructed and arranged to engage the forepart of the upper within the welt crease, means for moving the forepart wipers heightwise of the upper in order to wipe the upper on its last heightwise thereof toward the last bottom, and yielding means for urging the heel wipers toward each other whereby said members, bearing against the shoe bottom, oppose movement of the last heightwise thereof during the heightwise wiping operation.
10. A lasting machine having in combination wipers for wiping an upper on its last heightwise thereof toward the last bottom, and lasting wipers constructed and arranged to hold the last against heightwise movement during the heightwise wiping of the upper.
11. A lasting machine having in combination wipers for wiping a pre-welted upper on its last heightwise thereof to the last bottom thereby to position the welt for the reception of an outsole, and means for holding the last against heightwise movement during the heightwise wiping operation comprising lasting members constructed and arranged to engage the shank portion of the upper in the welt crease.
12. A lasting machine having in combination wipers for wiping a pre-welted upper on its last heightwise thereof to the last bottom thereby to position the welt for the reception of an outsole, and means for holding the last against heightwise movement during the heightwise wiping operation comprising a pair of elongated heel wipers extending forwardly of the supported last to the region of the ball line, said wipers being constructed and arranged to engage the upper in the welt crease.
13. In a machine for use in the manufacture of shoes, a sole-laying member, a slide to which the member is pivoted, a carrier for the slide constructed and arranged to swing about a vertical axis, means for adjusting the slide lengthwise thereof relatively to the carrier, and adjusting means for so locating the member that its longitudinal median line is arranged at any one of a series of predetermined angles to the slide.
14. In a machine for use in the manufacture of shoes, a sole-laying member movable in an arcuate path to and from operative position, an adjustable stop for arresting the member in any one of a series of predetermined positions lengthwise of a supported shoe, means for adjusting the member widthwise of the supported shoe, and adjusting means for so locating the member that its longitudinal median line is arranged at any one of a series of predetermined angles to the axis of its arcuate path of movement. 5
15. In a machine for use in the manufacture of shoes, a sole-laying member movable to and from operative position, an adjustable stop for arresting the member in any one of a series of 15 predetermined positions lengthwise of a supported shoe, and means for indicating said series of predetermined positions in terms of shoe sizes.
16. In a machine for use in the manufacture 20 of shoes, a sole-laying member, a slide to which the member is pivoted, a carrier for the slide constructed and arranged to swing about a vertical axis, means for indicating the position of the slide lengthwise thereof relatively to the carrier, adjusting means for so locating the member that its longitudinal median line is arranged at any one of a series of predetermined angles to the slide, and means for indicating said adjustment. 25
17. In a machine for use in the manufacture 30 of shoes, a sole-laying member, a slide to which the member is pivoted, a carrier for the slide constructed and arranged to swing about a vertical axis, means for adjusting the slide lengthwise thereof relatively to the carrier, adjusting means 35 for so locating the member that its longitudinal median line is arranged at any one of a series of predetermined angles to the slide, and co-related devices for indicating the respective adjustments. 40
18. In a machine for use in the manufacture 45 of shoes, a sole-laying member movable in an arcuate path to and from operative position, an adjustable stop for arresting the member in any one of a series of predetermined positions lengthwise of a supported shoe, means for adjusting the member widthwise of the supported shoe, adjusting means for so locating the member that its longitudinal median line is arranged at any one of a series of predetermined angles to the 50 axis of its arcuate path of movement, and co-related measuring devices for indicating the respective adjustments. 50
19. In a machine for use in the manufacture 55 of shoes, means for supporting in inverted position a last with an upper thereon, a sole-laying member movable in an arcuate path to and from operative position, an arm, means for suspending the member on the arm constructed and arranged to permit adjustment of the member to 60 the profile of the bottom of the supported last and to permit adjustment of the member about a vertical axis extending through the point of suspension, adjusting means for swinging the member about its heightwise axis in order to locate the member with its longitudinal median line arranged at any one of a series of predetermined angles to the arm, said adjusting means comprising a plate extending laterally from the member, a slide supported by the arm for movement lengthwise of the arm, a screw threaded to the slide, and connections from the laterally extending plate to said screw constructed and arranged to permit adjustment of the member to 65 the profile of the last bottom. 60
- 70
- 75

20. In a machine for use in the manufacture of shoes, means for supporting in inverted position a last with an upper thereon, a sole-laying member adjustable to the profile of the bottom of the supported last, said member being movable in an arcuate path to and from operative position, an adjustable stop for arresting the member in any one of a series of predetermined positions lengthwise of a supported shoe, means for adjusting the member widthwise of the supported shoe, adjusting means for so locating the member that its longitudinal median line is arranged at any one of a series of predetermined angles to the axis of its arcuate path of movement, and co-related devices for indicating the respective adjustments. 5
21. In a machine for use in the manufacture of pre-welted shoes, means for supporting in inverted position a last with an upper thereon, a series of plates constructed and arranged to underlie the welt throughout substantially its entire extent in order to support it for the sole-laying operation, a sole-laying member movable in an arcuate path to and from operative position, an arm, means for suspending the member on the arm constructed and arranged to permit adjustment of the member to the profile of the bottom of the supported last and to permit adjustment of the member about a vertical axis extending through the point of suspension, adjusting means for swinging the member about its heightwise axis in order to locate the member with its longitudinal median line arranged at any one of a series of predetermined angles to the arm, said adjusting means comprising a plate extending laterally from the member, a slide supported by the arm for movement lengthwise of the arm, a screw threaded to the slide, and connections from the laterally extending plate to said screw constructed and arranged to permit adjustment of the member to the profile of the last bottom. 10
22. In a machine for use in the manufacture of pre-welted shoes, a jack post for supporting in inverted position a last with a pre-welted upper thereon, a pair of lasting wipers for overwiping the portion of the upper extending rearwardly from the region of the ball line, means for yieldingly holding the wipers advanced, and means for moving the jack post rearwardly of the supported last to cause the wipers to engage the upper in the welt crease and to overlie the margin of the last bottom. 15
23. In a lasting machine, a heel pad and a heel wiper characterized by interengaging surfaces on the wiper and the pad, respectively, arranged to arrest the wiper by their interengagement and characterized further by the disposition of a portion of the thickness of the wiper below the level of the top of the pad. 20
24. In a lasting machine, a heel pad and a heel wiper characterized by interengaging beveled surfaces on the wiper and the pad, respectively, arranged to arrest the wiper by their interengagement and characterized further by the disposition of the major portion of the thickness of the wiper below the level of the top of the pad. 25
25. In a lasting machine for lasting pre-welted shoes, a heel pad and heel wipers constructed and arranged to engage a pre-welted upper in the welt crease, and characterized by interengaging beveled surfaces on the wipers and the pad, respectively, arranged to arrest the wipers by their interengagement. 30
26. In a lasting machine for lasting pre-welted shoes, a heel pad and a pair of heel wipers char- 35
- acterized by inter-engaging beveled surfaces on the wipers and the pad, respectively, arranged to arrest the wipers by their interengagement, each of said wipers being provided with a marginal portion extending beyond its beveled surface for engagement within the welt crease. 40
27. In a lasting machine for lasting pre-welted shoes, a heel pad and a heel wiper characterized by interengaging surfaces on the wiper and the pad, respectively, arranged to arrest the wiper by their interengagement, said wiper being provided with a thin marginal portion arranged, when the wiper is in its overwiped position, to extend beyond the shoe-engaging face of the heel pad and into the welt crease. 45
28. In a lasting machine for lasting pre-welted shoes, a heel pad and a heel wiper characterized by interengaging surfaces on the wiper and the pad, respectively, arranged to arrest the wiper by their interengagement, said wiper being provided with a marginal portion extending to a measured extent beyond its pad-engaging surface. 50
29. In a lasting machine, a heel pad and heel wipers characterized by interengaging surfaces on the wipers and the pad, respectively, arranged to arrest the wipers by their interengagement, and means for adjusting the pad lengthwise and widthwise of the wipers. 55
30. In a lasting machine, a shoe support, heel wipers, a heel pad, a carrier for the pad, arms pivoted to the carrier and arranged to swing toward and from the outer surfaces of the respective end portions of the pad, and a presser members for each of said arms constructed and arranged to move the arms independently toward the supported shoe in order to impart a like movement to the adjacent end portions of the heel pad. 60
31. In a lasting machine, heel wipers and toe wipers each of which is provided with a thin overwiping margin constructed and arranged to engage a pre-welted upper in the welt crease and a face extending downwardly from the overwiping margin, the major portion of the thickness of the wiper being disposed below the path of movement of the overwiping margin. 65
32. In a lasting machine, heel wipers and toe wipers each of which is provided with an overwiping margin of predetermined width and of such a thickness that said margin may advance between the welt and the upper of a pre-welted shoe substantially to the seam whereby the welt is secured to the upper without stretching the seam, said wipers being characterized by a beveled face extending downwardly and outwardly from the overwiping margin. 70
33. In a lasting machine for lasting pre-welted shoes, heel wipers and toe wipers, each of said wipers being provided with a thin overwiping margin constructed and arranged to engage an area of the top face of the welt bounded by the seam which secures the welt to the upper and to support the welt in position to receive an outsole, each of said wipers being characterized by a beveled face extending downwardly from the overwiping margin at an obtuse angle thereto. 75
34. In a lasting machine, heel wipers and toe wipers, each of said wipers being provided with a thin overwiping margin, the upper surface of which is a rectilinear extension of the upper surface of the body portion of the wiper, said toe wipers only being characterized by a beveled face extending downwardly from the overwiping margin at an angle of about 130° thereto. 80

35. In a lasting machine, lasting wipers the wiping edges of which, when the wipers are advanced, substantially enclose the bottom of a last in the machine, at least one of said wipers being provided with an abutment constructed and arranged to engage a portion of an upper on the last thereby to obstruct movement of the last widthwise thereof.

36. In a lasting machine, means for supporting a last having an upper thereon, toe wipers and heel wipers the wiping edges of which when the wipers are advanced generally define substantially the entire outline of a shoe bottom, said toe wipers being provided with abutment faces constructed and arranged to engage portions of the upper adjacent to opposite side faces of the last and thereby to hold the forepart of the last from movement widthwise thereof.

37. In a lasting machine, means for supporting a last having an upper thereon, toe wipers and heel wipers the wiping edges of which when the wipers are advanced generally define substantially the entire outline of a shoe bottom, said toe wipers being provided with abutment faces constructed and arranged to engage portions of the upper adjacent to opposite side faces of the last and thereby to hold the forepart of the last from movement widthwise thereof, and a heel-embracing band constructed and arranged to hold the rear part of the last from movement widthwise thereof.

38. In a machine for lasting pre-welted shoes, means for supporting a last having an upper thereon, and end-embracing wipers the wiping edges of which, when the wipers are advanced, substantially enclose the bottom of a last in the machine, each of said wipers being provided with an overwiping margin constructed and arranged to extend between the welt and upper substantially to the seam whereby the welt is secured to the upper without separating the welt and upper at the seam line, at least one of said wipers being provided with an abutment constructed and ar-

ranged to engage a portion of the upper adjacent to a side face of the last thereby to arrest movement of the last widthwise thereof in one direction.

39. In a lasting machine, a heel-embracing band and heel wipers characterized by inter-engaging surfaces on the wipers and the band, respectively, arranged to arrest the wipers by their interengagement, and toe wipers each of which is provided with a thin overwiping margin and a beveled face extending downwardly and outwardly from the everlasting margin, said heel wipers and toe wipers each being characterized by the disposition of a portion of the thickness of the wiper below the path of movement of its overwiping margin.

40. In a lasting machine, a heel wiper constructed and arranged to overwipe the heel and shank portions of a supported shoe, said wiper being constructed and arranged to operate upon shoes within a run of sizes, the extent of the wiper lengthwise of the supported shoe being measured by the smallest size of shoe within the run while the profile of the wiper is determined by the profile of the largest size of shoe within the run.

41. In a lasting machine, a heel wiper constructed and arranged to overwipe that portion of a supported shoe extending from its heel end to the region of the ball line, said wiper being constructed and arranged to operate upon shoes with in a run of sizes, the extent of the wiper lengthwise of the supported shoe being measured by the smallest size of shoe within the run while the profile of the wiper is determined by the profile of the largest size of shoe within the run and the contour of the wiping edge of the wiper is determined by the contour of the bottom of a last of an intermediate size.
